UNITED STATES PATENT OFFICE

MAX POPPER, OF BROOKLYN, NEW YORK

VENTILATING STRIP FOR HATS

Application filed July 11, 1928. Serial No. 291,960.

This invention is directed to an improvement in self-conforming, ventilating sweatbands for hats, caps and other headwear, wherein the fit of the hat is comfortable to the head of the wearer, and the space within the hat above the head is thoroughly and completely ventilated at all times.

The primary object of the present invention is the provision of a section yieldable under pressure and formed to provide openings which extend through the section from the lower to the upper edge as in use, the elasticity of the section providing the self-conforming feature and the openings in the section affording free passage of air to promote complete ventilation and air circulation of the space within the hat while the latter is in use.

A further object of the invention is the provision of a ventilating, self-conforming strip cut away on its inner and outer surfaces for a portion of the vertical dimension thereof in order to provide for the securing of the sweat-band to the section to avoid projection and prevent disconnection of the sweat-band, the cut away portion on the outer surface of the strip providing for the reception and securing to the strip of the cloth band through which the strip and sweat-band are secured to the hat.

A further object of the present invention is the provision in a self-conforming ventilating strip of an integral extension designed to underlie the meeting edges of the sweat-band, and to permit such meeting edges to be secured in an even, fixed relation to facilitate the assemblage and materially improve the finish at this point.

The invention is illustrated in the accompanying drawings, in which:

Figure 1 is a broken plan view of a portion of a hat, showing the improved self-conforming ventilating strip in position.

Figure 2 is a vertical section of the same.

Figure 3 is a plan view of the ventilating strip showing the same as an endless member conforming in size to the hat for which it is adapted.

Figure 4 is a broken perspective of the ventilating strip showing the integral tab to

which the sweat-band ends are secured, and also showing the cloth band for securing the strip to the hat.

Figure 5 is a broken perspective view of the strip as constructed of indeterminate lengths and adapted to be cut for the particular size of hat to which it is to be secured.

The improved self-conforming ventilating strip, indicated at 1, is a comparatively narrow section of yieldable or more or less elastic material formed throughout its length with a series of openings 2, which open through the upper and lower surfaces of the strip as the same is arranged when in applied position.

The width of the strip, that is, its dimension vertically of the hat as the strip is applied, is designed to vary with the character of hat with which the strip is used. For example, in caps and the like the strip will necessarily be of comparatively narrow width, while in stiff hats, and particularly silk hats, the strip will be of greater width in order to present a greater length of yielding surface to the head of the wearer.

The outer surface of the ventilating strip, that is, the surface next the hat as the strip is applied, is cut away or reduced in width, as at 3, this cut away portion extending from the upper edge to a point immediately adjacent the lower edge, and there presenting a somewhat inclined shoulder 4. This cut away portion provides for the cementing to the strip of the cloth or like band 5, the fold of which immediately underlies the shoulder 4, and the free section 6 of which band is utilized for stitching the strip and connected sweat-band to the hat in the usual manner.

The inner surface of the ventilating strip is similarly cut away at 7, terminating in an abrupt shoulder 8 adjacent the lower edge of the strip, providing a recess in which the sweat-band 9 is cemented. The depth of the recess is equal to the thickness of the sweat-band, so that in applied position the juncture of the sweat-band and ventilating strip at the shoulder 8 presents a smooth, unbroken surface to thereby avoid projection which would otherwise tend to the discomfort of the wearer. As the lower edge of the sweat-band fits snugly against the shoulder 8, it is apparent

that when applied there is no liability of any projecting portion of the sweat-band inwardly of the lower edge of the ventilating strip. Thus, there is no possibility of the sweat-band being disconnected from the ventilating strip in the continued application of the hat, as would be liable if the sweat-band presented a projection inwardly of the strip.

The sweat-band proper is of course a proper length of appropriate material which, when applied to the hat, presents meeting ends, indicated at 10. In ordinary hat construction, these meeting ends are joined by a separate piece of material secured to the cloth band, involving additional labor and expense and at the same time necessitating an unfinished appearance of the hat at this point. To avoid this additional labor and unfinished appearance, the ventilating strip of the present invention is provided with an upstanding, integral comparatively thin tab 11, which underlies the meeting ends 10 of the sweat-band and to which such meeting ends may be cemented or otherwise secured. Thus, the sweat-band may be secured in a manner to positively prevent the separation of its ends in a simple, expeditious manner, avoiding undue projection at this point and materially increasing the finished appearance of the hat.

The ventilating strip is to be constructed so that it is yieldable to the pressure of the head of the wearer when the hat is in place. For this purpose, it is apparent that the ventilating strip may be constructed of soft rubber or other similar material, or if desired may be made of paper strips between which a convolute length of paper is arranged to provide the ventilating openings. Any and all materials capable of affording ventilating openings and the same time presenting the self-conforming feature are contemplated so long as such strip presents on its respective inner and outer surfaces the recesses for the reception of the sweat-band and cloth band, as previously described.

As an important detail of the present invention, it is to be understood that the ventilating strip may be constructed of an endless length of material presenting a ring-like member of a size to fit the particular size of hat for which it is designed. This will materially facilitate the application of the sweat-band, cloth band and ventilating strip, without undue projection at any point, avoiding discomfort as a result of such projection and materially increasing the finished appearance of this portion of the hat. This particular form of the hat band is illustrated in Figure 3.

It is of course also contemplated that the ventilating strip be made in lengths, as indicated in Figure 5, so that a length appropriate to the size of the hat with which it is being used may be cut from the main length and the strip applied. In this use, the ends

of the strip may be cemented or otherwise secured together to avoid lapping and thus avoid undue projection.

What is claimed to be new is:

1. A ventilating strip for hats or the like, comprising a yieldable strip formed with ventilating openings therethrough, the inner surface of the strip being recessed to receive the hat band, the outer surface of the strip being recessed to receive the cloth attaching band.

2. A ventilating strip for hats and the like, comprising a yieldable strip formed with ventilating openings, said strip being formed on its inner surface with a recess to receive the sweat-band, and a tab projecting integrally from the strip to underlie the meeting ends of the sweat-band and to which said meeting ends are secured.

3. A self-conforming ventilating strip for hats and the like, comprising a yieldable strip formed with openings extending vertically therethrough, the lower edge of the strip being rounded and the inner surface of the strip being formed immediately above the rounded edge with a shoulder coextensive in width with the thickness of the sweatband to be used and forming a support for such sweatband, with the inner surface of the strip above the shoulder providing a flat surface to which the sweat band may be secured, the rounded lower edge of the strip merging into said shoulder.

4. A self conforming ventilating strip for hats and the like, comprising a yieldable strip formed with ventilating openings, the lower portion of the inner surface being formed with a sweatband supporting shoulder, the strip having an integral upstanding section to which the meeting ends of the sweatband above the strip may be secured.

In testimony whereof I affix my signature.
MAX POPPER.
